UNITED STATES PATENT OFFICE.

WILLIAM H. CARTER, OF NEEDHAM HEIGHTS, MASSACHUSETTS.

DESIGN FOR A KNITTED SACHET-BAG WITH ORNAMENTAL BORDER.

43,417.

Specification for Design.

Patented Jan. 7, 1913.

Application filed September 12, 1912. Serial No. 720,103. Term of patent 14 years.

To all whom it may concern:

Be it known that I, WILLIAM H. CARTER, a citizen of the United States, residing at Needham Heights, in the county of Norfolk and State of Massachusetts, have invented a new, original, and ornamental Design for a Knitted Sachet - Bag with Ornamental Border, of which the following is a specification, reference being had to the accompanying drawing, forming part thereof.

The figure is a plan view of my improved knitted sachet bag with ornamental border.

I claim:

The ornamental design for a knitted sachet bag with ornamental border, as shown.

In testimony whereof, I have signed my name to this specification in the presence of two subscribing witnesses.

WILLIAM H. CARTER.

Witnesses:

SAMUEL CUNNINGHAM,
PRESTON MITCHELL.
